(57) CLAIM

The ornamental design for a golf club head cover, as shown and described.

DESCRIPTION

FIG. 1 is a front perspective view of the golf club head cover of the present invention;

FIG. 2 is a bottom perspective view thereof;

FIG. 3 is a top plan view thereof;

FIG. 4 is a side view thereof;

FIG. 5 is a bottom plan view thereof;

FIG. 6 is a front plan view thereof;

FIG. 7 is an additional side view thereof;

FIG. 8 is a rear plan view thereof; and,

FIG. 9 is a front plan view with flap opened.

The broken line showing is for illustrative purposes only and forms no part of the claimed design.
